UNITED STATES PATENT OFFICE.

HARRY D. LANGTON, OF CLEVELAND, OHIO.

STEAM-ENGINE.

SPECIFICATION forming part of Letters Patent No. 788,723, dated May 2, 1905.

Application filed February 16, 1904. Serial No. 193,809.

To all whom it may concern:

Be it known that I, HARRY D. LANGTON, a citizen of the United States, residing at Cleveland, in the county of Cuyahoga and State of Ohio, have invented a new and useful Improvement in Steam-Engines, of which the following is a specification.

My invention relates to an engine especially adapted for use with automobiles; and the object of the invention is a compact durable single-acting compound steam-engine having high and low pressure cylinders.

A further object is to combine within a single casing all the working parts of two engines of this type, the low-pressure cylinders being arranged adjacent and parallel to each other and having a common exhaust-pipe.

The advantages of applying a single-acting engine to a vehicle may be briefly set forth as absence of slide-valves, stuffing-boxes, and cylinder-lubricators, that superheated steam may be used, and that the crank connections can run free, eliminating pounding, adding to the life of the bearings, and avoiding the jars common to many automatically-propelled vehicles.

Briefly stated, my invention consists of four vertically-arranged cylinders parallel to each other and open at their lower ends, the lower ends of all the cylinders being in the same horizontal plane. The casing forming the outer walls of the cylinders extends downward below the lower ends of the cylinders and forms a casing in which work the pitmen, a crank-shaft passing longitudinally through and being journaled in the ends of the casing, the said shaft having a gear-wheel fixed thereon. A cam-shaft has its ends journaled in the ends of the casing and is arranged parallel to and above the crank-shaft, and a gear-wheel is slidably keyed to the cam-shaft and is adapted at all times to mesh with the gear-wheel on the crank-shaft. The cam-shaft is slideable, and means are provided whereby the gear-wheel on the said shaft is held against longitudinal movement during such movement of the cam-shaft. On the cam-shaft are arranged oppositely-formed sets of cams. The valve-stems extend below the lower open ends of the cylinders and are actuated by the said

cams, one set of cams being in engagement with the valve-stems during forward movement and the other set being brought into engagement with the said stems by sliding the cam-shaft, thus reversing the engine. Steam 55 is admitted into the high-pressure cylinders, which are of less diameter than the low-pressure cylinders, and the steam is then passed into the latter, from which it is exhausted through a common exhaust-pipe. 60

My invention also consists in the novel features of construction and combination of parts particularly brought out in the claims and shown in the accompanying drawings, in which— 65

Figure 1 is a view of my engine in elevation. Fig. 2 is a vertical section taken on the line 2 2 of Figs. 5 and 6. Fig. 3 is an end elevation. Fig. 4 is a vertical transverse section on the line 4 4 of Fig. 2. Fig. 5 is a plan 70 view. Fig. 6 is an irregular section on the line 6 6 of Fig. 2. Fig. 7 is a detail sectional view on the line 7 7 of Fig. 5, the valves and springs being shown in elevation. Fig. 8 is a similar sectional view on the line 8 8 of Fig. 75 5, and Fig. 9 is a similar view on the line 9 9 of Fig. 5. Fig. 10 is a detail view of one of the valve-throwing arms.

In the drawings, A represents two high-pressure cylinders, and B two low-pressure cylinders arranged between the cylinders A, the cylinders A having a less diameter than the cylinders B and the cylinders being integral. The cylinders are all downwardly open and are closed at their upper ends, the ends being 80 integral with the side walls of the cylinders. These cylinders are substantially all of the same length. The space immediately below the cylinders is inclosed by a sectional casing, the upper section A' of the casing being 85 formed integral with the lower portion of the outer walls of the cylinder, as is clearly shown in Fig. 2. The lower section A'' of the casing is bolted to the upper section and comprises 90 the bottom A³. 95

A shaft C passes longitudinally through the casing and is journaled in suitable boxes A⁴, formed at the juncture of sections A' and A'' of the casing, the boxes being provided with suitable bearings A⁵. The shaft C is provided 100

with suitable cranked portions C', and intermediate the ends of the casing the shaft is supported by bearings A⁶, carried by the vertical depending wall A⁷, which extends downward from between the two low-pressure cylinders B. Pistons C² are arranged in the high-pressure cylinders A and are connected by suitable piston-rods or crank-arms C³ to the outer cranked portions, respectively, of the crank-shaft C. Pistons C⁴ are arranged in the low-pressure cylinders B and are connected to the intermediate cranked portions C' by the piston-rods C⁵. These pistons are hollow and downwardly open. In each piston inwardly-extending sleeves are arranged, as shown at C⁶, in horizontal alinement and spaced apart and having a bore extending through the side walls of the piston. The upper portion of the piston-rods extends between the inner ends of the sleeves in the respective pistons and the sleeves form bearings for stub-shafts C⁷, the ends of which rest in the sleeves, the shafts passing through the upper portions of the piston-rods, and each piston-rod is thus practically journaled at its upper end in its respective piston.

Above the cylinders A are arranged valve-casings D, and ports or passage-ways D' lead from these casings D into the upper portion of the cylinders A. These casings extend over the adjacent cylinders B, and ports D² lead from the casings D into the cylinders B. Arranged in the casings D between the passage-ways D' and D² are valve-seats D³ and valves D⁴, which coöperate with the said seats. The upper portions of the casings have an inferiorly-threaded opening formed therein in which fits a threaded cap E, recessed on its under face. The upper portion of a coiled spring E' is arranged in the recess of each cap and bears at its lower end on the upper face of the valve below it. All the valve-casings are fitted with these caps and springs, which are all designated by the same reference characters. The valves D⁴ control the passage of steam from the high-pressure cylinders A to the low-pressure cylinders B. Arranged adjacent the casings D are valve-casings F, communicating by inlet-ports F' with the interiors of the cylinders A, and live superheated steam is admitted to the casings F through the steam-inlets F². Intermediate the casings described is a twin casing G, and exhaust-passages G' lead from the low-pressure cylinders B. In the outer side of this casing is a suitable exhaust-port G² common to the passages G' and shown most clearly in Fig. 1. In the casings F are arranged valve-seats and coöperating valves F³, controlling passage of steam from the inlets F² to the ports or passages F', and in the twin casing G are valve-seats and coöperating valves G³, controlling the exhaust from the cylinder B, the said valves and seats being identical in construction with the valve-seats D³ and valves D⁴.

Below the casings E, F, and G are cylindrical depending sleeves H, each having a longitudinal bore therethrough enlarged at its lower end, and a packing-nut H' is threaded into the lower portion of each sleeve. Extending from the valves in these casings and through the sleeves H are valve-stems H², leading from the valves F³, and stems H³, leading from the valves G³. The valve-stems H⁴ extend from the valves D⁴ and lead downward through suitable vertical grooves or slots in the cylinder-walls, as shown in Fig. 8.

Above the boxes A⁵ are formed boxes J on the section A' of the casing, and in these boxes J are journaled the ends of a cam-shaft J', arranged parallel to and above the plane of the shaft C, the shaft being in alinement with the valve-stems H² and H³. On the cam-shaft J' are arranged two sets of oppositely-formed cams J² J³, arranged alternately and in pairs, the cams J² and J³ of each pair being connected by an inclined or beveled face J⁴. The lower ends of the valve-stems H² and H³ normally rest on the arms K², that are in alinement with the said cams J². The valve-stems H⁴ are out of alinement with the cam-shaft J', and to actuate these stems arms K are pivoted to a shaft K', parallel with and slightly above the plane of the cam-shaft J', and the free slightly-curved ends of the arms K rest normally on the cams J², which actuate the valve-stems H⁴, the lower ends of the stems resting on the arms K. The arms K are also pivoted to the shaft K'. These cams regulate the throw of the valves, and to reverse the engine it is only necessary to slide the cam-shaft J so as to bring under the valve-stems the cams J³ in place of the cams J². A grooved collar L is rigidly secured to the cam-shaft J', and a vertically-arranged sleeve L' is arranged on one side of the casing or section A' and opens downwardly within same. A lever-shaft L² is rotatably carried by this sleeve L', and to the lower end of the shaft is fixed a collar L³, from which extends a curved arm L⁴, bifurcated at its free end, the bifurcated members of the arm resting in the groove of the collar L. By swinging the lever L² so that the vertical portion of the lever-shaft will rotate in the sleeve L', the free bifurcated end of the arm L⁴ will be swung to the right or left and bearing on the fixed collar L will shift or longitudinally slide the cam-shaft J'.

To drive the cam-shaft, a gear-wheel M is fixed on the shaft C and a gear-wheel M' is keyed on the cam-shaft J', so that it will mesh with the gear-wheel M. To the gear-wheel M' is secured a grooved collar M², and into the groove of this collar extends the lower end of a lug M³, whereby the collar M² and gear-wheel M' are held against longitudinal movement when the cam-shaft is shifted longitudinally by the reversing-lever L². On one end of the shaft C, I have shown a

sprocket-wheel N, and a suitable sprocket-chain may be used to transmit the rotation of the wheel N to the axle of the vehicle, or any other suitable means may be employed to 5 transmit the rotation to the wheels of the vehicle with which it is used. A suitable cam-wheel O is arranged on the opposite end of the shaft C, and a suitable rod O', in engagement with the said cam-wheel O, operates a 10 pump of any kind, (not shown,) such as is commonly used with engines of this type.

Steam is admitted to the high-pressure cylinders A from any desired source. The arrangement of the cams and valves is such that 15 steam is admitted to one of the cylinders A, and the downward stroke of the piston in said cylinder commences during the upstroke of the piston in the other high-pressure cylinder A. At this point in the operation the 20 valve D⁴, controlling passage of steam from the high-pressure cylinder A, in which the steam is being admitted, is closed and the piston in the adjacent low-pressure cylinder B is on the upstroke, the steam in the said cylinder being forced outward through the exhaust-port G² by the ascending piston C⁴, the valve G³, controlling passage of steam from 25 said cylinder, being open. On the other side of the engine—the right-hand side in Fig. 2— 30 the valve F³ is closed, valve D⁴ is open, and steam is being forced by the ascending piston C² through the passage-ways D' and D² into the adjacent low-pressure cylinder B, and the piston C⁴ in the said last-mentioned cylinder will 35 be on the downstroke. It is obvious, therefore, that the pistons in the two high-pressure cylinders are oppositely acting, that the pistons in the two low-pressure cylinders are oppositely acting, and that the pistons in each 40 high-pressure cylinder and its adjacent or co-acting low-pressure cylinder are oppositely acting.

Superheated steam may be admitted to the high-pressure cylinders, permitted to expand 45 therein, and then be admitted into the low-pressure cylinders, where the second expansion takes place against a piston of greater area than the piston against which the first expansion took place.

50 At the ends of the section A² of the casing a vertical partition P is formed, having a vent P' therein adjacent the bottom of the casing. A vent P² leads from the bearings of the shaft C downward and opens at its lower end into 55 the chamber formed by each partition P, and oil which works along the shaft C toward either end of the shaft escapes through the vents P² and returns to the lower portion of the casing through the vent-opening P', and 60 is thus prevented from leaking and running over upon the exterior of the casing and splattering the carriage. All the bearings are lubricated by the splash of oil by the crank-shafts, and suitable oil grooves and vents are 65 placed where found desirable. The piston

heads and cylinders are lubricated from the same source. This keeps the oil from mixing with the steam and dispenses with an oil filter or eliminator. Suitable packing-rings are used on the pistons, and it is obvious that the 70 casings and cylinders may be bolted, braced, ribbed, or strengthened in any desired manner, according to the use to which the engine is to be placed. By having the valve-stems H² and H³, which are in alinement with the 75 cams J², rest on the arms K², which are similar to the arms K, lateral thrust on the said valve-stems is avoided.

Having thus fully described my invention, what I claim as new, and desire to secure by 80 Letters Patent, is—

1. An engine of the type described comprising high and low pressure cylinders arranged in sets, pistons adapted to work in said cylinders, valves controlling admission of steam 85 into said high-pressure cylinders, valves controlling passage of steam from the high-pressure cylinder of each set to the low-pressure cylinder of the same set, and means for closing the valve admitting steam to the high-pressure cylinder of one set of cylinders when the valve controlling the passage of steam from the high-pressure cylinder to the low-pressure cylinder of the adjacent set is open. 90

2. An engine of the kind described comprising four cylinders arranged parallel to each other and open at one end the outer cylinders being of less diameter than the intermediate cylinders, valve-casings arranged at the closed ends of said cylinders, means for admitting live steam into the two outer casings, the said casings having inlet-ports opening into the said outer cylinders, respectively, valves in said casings controlling said ports, two of said casings having passage-ways leading through the said casings from the outer cylinders to the adjacent cylinders, valves in 100 said casings controlling the said passage-ways, a twin casing having passage-ways leading from the intermediate cylinders into the casing, said twin casing having an exhaust-port common to each of said passage-ways, a valve in each of said passage-ways, means for actuating all of the said passage-ways, and pistons 105 adapted to work in the said cylinders. 110

3. The combination with a plurality of downwardly-open cylinders, valves adapted to control admission of steam to and from said cylinders, depending valve-stems connected at their upper ends to the valves, pistons in the cylinders, a crank-shaft journaled below and at right angles to said cylinders, piston-rods connecting the pistons and crank-shaft, a 120 slideable cam-shaft parallel to the crank-shaft, a gear-wheel on the crank-shaft, a second gear-wheel on the cam-shaft adapted to constantly mesh with the gear-wheel on the crank-shaft, two sets of oppositely-formed cams on the cam-shaft, said cams being arranged in pairs, the cams of each pair being connected by an 125 130

inclined face, the said cams being adapted to actuate the valve-stems, and means for sliding the cam-shaft to bring into operation either set of cams.

5. 4. A single-acting compound-engine comprising two high-pressure cylinders and two low-pressure cylinders arranged intermediate the high-pressure cylinders, valves adapted to control the admission of steam to the high-pressure cylinders, valves adapted to control passage of steam from the high-pressure to the low-pressure cylinders, a cam-shaft arranged transverse to the said cylinders, cams arranged on the said shaft, a plurality of pivoted arms having their free ends resting on the said cams, vertically-movable, depending valve-stems having their free ends resting upon said arms, pistons in the cylinders, a crank-shaft, and means for transmitting rotation of the crank-shaft to the cam-shaft, as and for the purpose set forth.
- 10 5. An engine of the kind described comprising a plurality of cylinders, valve-casings

carried by the said cylinders, valves in the said casings, a cam-shaft arranged adjacent the 25 said cylinders, two sets of oppositely-formed cams carried by the said shaft and arranged in pairs, the cams of each pair being connected by a beveled face, stems connected to the valves and adapted to be actuated by the said 30 valves, pistons in the cylinders, a crank-shaft parallel to the cam-shaft, piston-rods connected at one end to the pistons and at the opposite end to the crank-shaft, a gear-wheel fixed on the crank-shaft, an intermeshing gear-wheel keyed to the cam-shaft, a collar loose on the cam-shaft and secured to the keyed gear-wheel, said collar being grooved, a lug integral with one of the cylinders and extending into said groove, and means for sliding 35 the cam-shaft.
